ARMOR BLOCK FOR WATER WALLS
AND THE LIKEJohn Blizzard, Garden City, N. Y., assignor to
Foster Wheeler Corporation, New York, N. Y.,
a corporation of New York

Application April 2, 1930, Serial No. 440,919

25 Claims. (Cl. 122—6)

This invention relates to water tube boilers or the like, more particularly to the water walls thereof, and especially to an improved armor for the tubes of the water walls.

The general purpose of providing an armor for the water wall tubes of boilers or the like is to prevent the furnace fire from coming into direct contact with the tubes and also to form a continuous or substantially continuous wall comprised of a plurality of blocks of metallic or other refractory material all of which are in contact with the water-wall tubes, thus ensuring a wall in which substantially all the heat absorbed by it is usefully employed in heating or vaporizing the fluid within the tubes.

Heretofore, the armoring has usually been done by means of blocks of metal or other refractory material individually secured to the tubes either by means of bolts or the like or by shrinking them on the tubes. The blocks are usually made with a rectangular fire surface and it has been possible to mount the blocks on the tubes so as to be in close engagement or contact therewith only when the tubes happened to be on the exact centers for which they were designed. If, however, any of the tubes were out of alignment, as frequently happened, close contact between the blocks and tubes has only been obtained by bending and straining the tubes to fit the blocks since the blocks could not be moved laterally to an appreciable extent to closely fit the tubes for the reason that the blocks on any one tube were all confined between the blocks on adjacent tubes. In armored water walls where blocks have been used for the armor it has been found essential that the blocks be in close contact with the tubes for the reason, amongst others, that the rate of heat transfer through the blocks to the tubes is dependent upon the degree of closeness of the contact, and also because the blocks will be quickly damaged by the intense heat of the combustion chamber to which they are subjected if they become loose on the tubes. And in some instances where the blocks have been secured to the tubes by shrinking them thereon, cracks have developed in the furnace side of the blocks, as a result of which the blocks have spread away from the tubes and have been burned.

Moreover, where the armor blocks have been bolted or similarly secured to the tubes by means other than shrinking the blocks on the tubes, it has heretofore generally been possible to obtain an area of contact between the tubes and the blocks of not more than one half the circumference of the tubes, and inasmuch as the rate of

heat transfer between the blocks and tubes is dependent upon the areas of contact therebetween, it is desirable that this area be as great as possible in order that the tubes may effectively cool the armor.

The present invention contemplates the provision of a block armor for the tubes of water walls which is characterized by the fact that close contact between the blocks and the tubes on which they are mounted will be readily obtained irrespective of the alignment of the tubes and without the necessity for bending or straining the tubes to fit the blocks. This characteristic is due primarily to the fact that the blocks and the means for securing them to the tubes are so designed that in the process of mounting and securing the blocks on the tubes the blocks are caused to adapt themselves to the tubes rather than necessitating the tubes adapting themselves to the blocks.

The invention also contemplates the provision of a block armor for the tubes of water walls wherein the blocks are bolted or secured to the tubes by means other than shrinking the blocks thereon and in which substantially more than one half the circumference of each of the tubes of the water wall is in contact with the armor.

Other features and objects of the invention will become apparent from the following description taken in connection with the accompanying drawings forming a part of this specification, in which:

Fig. 1 is a partial vertical sectional view of a tubular boiler having a water wall, the tubes of which are armored in accordance with the present invention;

Fig. 2 is a fragmentary horizontal sectional view of the boiler water wall taken on line 2—2 of Fig. 1 and on line 2—2 of Fig. 3, showing one form of my improved block armor;

Fig. 3 is a partial elevational view of the water wall shown in Fig. 2;

Fig. 4 is a view similar to Fig. 2 showing another form of my improved armor block, the section being taken substantially on the line 4—4 of Fig. 5;

Fig. 5 is a vertical sectional view taken on line 5—5 of Fig. 4;

Fig. 6 is a view similar to Fig. 4 showing still another form of the block; and

Fig. 7 is an elevational view of the block shown in Fig. 6.

Like reference characters refer to like parts throughout the several views.

Referring to the drawings, Fig. 1 shows a well-known type of water tube boiler having water tubes 10, a combustion chamber 11, front wall 55

12 and rear wall 13. As shown, the rear wall 13 is an armored water wall and has, vertically disposed therein, a series of parallel water tubes 14 extending between the lower and upper headers 15 and 16, respectively.

5 In accordance with this invention, the tubes 14 are armored by a plurality of block units 17 of metallic or of other suitable refractory material. In the form shown in Figs. 2 and 3, each 10 of the block units 17 comprises two separate but substantially similar block members or parts 18 and 19. Each part 18 and 19 has a substantially rectangular front fire surface 20 and a lateral cylindrical surface or recess 21 to receive the tubes 14 therein. The recesses 21 have a diameter approximately equal to the outside diameter of the water wall tubes 14 and a circumferential area substantially greater than one-fourth the surface area of the tube section adapted to be received in the recess. Each of the block parts is 15 also provided with a lateral convex surface 22, which will be hereinafter referred to as a reaction or eccentric surface. Each of these reaction surfaces is preferably located adjacent the fire surface of each part and on the side opposite to the tube receiving recess 21. The reaction surfaces 22 are preferably cylindrical surfaces eccentric to and of greater diameter than the cylindrical tube receiving recesses and with their 20 axes coinciding approximately with the lateral edges of the tube receiving recesses indicated on the drawings at 23. In this form, each part is also provided with a recess 24 adjacent the reaction surface 22 and an outwardly extending 25 projection or lip 25 having a central notch 26.

To mount the blocks on the tubes, the block parts 18 and 19 are placed together with their eccentric surfaces 22 in contact and the surfaces of their recesses 21 in engagement with the tubes 40 as shown in Fig. 2. The block parts are adapted to be secured to the tubes by means of a force member or a member adapted to exert a force in the proper direction on the block parts, such as a bolt 27. As shown, this bolt 27 is provided 45 with an elongated cylindrical head 28 adapted to be positioned in the recesses 24 and engaging the abutments or lips 25. A rigid bridge member 29 adapted to straddle or span the spaces between the tubes engaged by the block parts is mounted 50 on the shank of bolt 27 as shown, after which the nut 30 is threaded on the bolt.

It will readily be understood that when the nut 30 is turned up on the bolt 27 against the bridge member 29, a pulling force is exerted on the block parts between the tubes in a direction at right angles to the fire surface 20 of the block. This pulling force tends to swing the refractory members 18 and 19 on the tubes and to spread apart the rear portions of the block parts opposite to the fire surface 20 thereof, and causes a pressure between the parts along the line of contact of their eccentric surfaces 22. The result of this pulling force together with the force between the block parts, forces the parts against the tubes in close contact therewith due to the aforesaid force and the cam action of the eccentric surfaces. With this arrangement, the block parts are in effect wedged in between the tubes and it will be apparent that even though the tubes may be out of alignment, the blocks will readily adapt themselves to the tubes. This is accomplished, of course, entirely without any bending or straining of the tubes, for the reason that the blocks conform to the tubes rather than making it necessary for the tubes to conform to the position of

the blocks. With this arrangement, moreover, it is apparent that substantially more than one-half the circumference of each of the tubes of the water wall is in direct contact with the armor.

The form of the invention shown in Figs. 4 5 and 5 is substantially the same as the form just described, except that instead of the outwardly extending lips 25, the block parts 31 and 32 are provided with laterally extending and interfitting knuckles 33 and 34 having a pintle 35 therein. 10 In this form of the invention, the force member is also a bolt 36 which is provided with an apertured head through which the pintle 35 is passed. In practically all other respects, the block and the method of securing it to the tube is substantially the same as the form shown in Figs. 2 15 and 3.

In the form shown in Figs. 6 and 7, the block parts 38 and 39 are each provided with plane surfaces 40 forming extensions of the reaction surfaces 22. The force member in this form of the invention comprises an elongated, substantially T-shaped member 41, having a series of elongated apertures 42 and a cylindrical block contacting portion 43. Studs 44 threaded into the block parts 38 and 39 as shown, extend through the elongated apertures 42 of the force members 41 and have nuts threaded thereon. In this form, as the nuts are turned up against the member 41, the portion 43 of the force member 41 is forced 30 against the diverging surfaces of the block parts and tends to spread apart the portions thereof which are opposite the fire surfaces. A force is thereby set up between the block parts at their reaction surface contact and the parts are thus forced into close contact with the tubes much 35 in the same manner as in the forms of the invention previously described.

In all of the forms disclosed, the force member is adapted to act on the block parts in such manner that the portions of the parts of each block opposite to the fire surface thereof are spread apart. This results in a pressure between the parts at their reaction or eccentric surface contact and the combination of the spreading action 45 on one hand and the pressure between the parts on the other, results in the blocks being forced into close contact with the tubes on which they are mounted with no damage to the tubes which might result from bending or straining of the 50 tubes, and also results in the elimination of any danger of damage to the blocks by burning because of their looseness on the tubes, and due to the fact that substantially more than one-half the circumference of each of the tubes of the 55 water wall is in contact with the armor, effective cooling of the wall is assured.

It will be understood that if for any reason during service, the blocks become loose on the tubes, they may be readily tightened thereon to 60 maintain the close contact with the tubes, by merely taking down the removable fire brick wall at the rear of the water wall and tightening up on the force members of the loose blocks.

Although the invention has been shown and 65 described as particularly well adapted to the water walls of water tube boilers and the like, it will be apparent that it is equally well adapted to other types of heating apparatus, such as oil heaters and also may advantageously be used for baffles of boilers and similar apparatus.

70 Although many changes may be made in the forms of the invention herein disclosed, it is nevertheless intended that the invention be limited only by the scope of the appended claims.

What I claim is:

1. The combination with spaced tubes, of a block unit mounted thereon and therebetween comprising two refractory members, said members having curved tube recesses and curved contacting surfaces eccentric thereto, a rigid member, and tension means engaging the refractory members and the rigid member for clamping the block unit to the tubes. 5
- 5 2. The combination with spaced tubes, of a block unit mounted thereon and therebetween comprising two block members, said members having curved tube recesses and curved contacting surfaces eccentric thereto, a rigid member, 10 means engaging the block members and the rigid member for clamping the block unit and the rigid member to the tubes. 15
- 20 3. The combination with spaced tubes, of a block unit mounted thereon and therebetween comprising two block members, said members having curved tube recesses and curved contacting surfaces eccentric thereto, a rigid member, and threaded means engaging the block members and the rigid member to clamp the block 25 unit to the tubes.
- 30 4. The combination with spaced tubes, of a block unit comprising two block members, said members having curved tube recesses, curved contacting surfaces opposite said recesses and eccentric with respect thereto and said members having abutments, a rigid member, and stress means engaging the abutments on the block members and the rigid member and operative to swing the block members on the tubes to wedge 35 the block unit by cam action of the eccentric contacting surfaces.
- 40 5. The combination with spaced parallel cylindrical tubes, of a block unit mounted thereon and therebetween comprising two block members, said members having curved tube recesses, contacting surfaces opposite said recesses and eccentric with respect thereto and said members having abutments, a rigid member spanning the space between and contacting said tubes, and stress means acting between the abutments on the block members and the rigid member and operative to swing the block members on the tubes to wedge the block unit by cam action of the eccentric 45 contacting surfaces.
- 50 6. The combination with spaced parallel cylindrical tubes, of a block unit mounted thereon and therebetween comprising two block members, said members having curved tube recesses, curved contacting surfaces opposite said recesses and eccentric with respect thereto and said members having abutments, a rigid member spanning the space between and contacting said tubes, and threaded members acting between the abutments on the block members and the rigid member 55 and operative to swing the block members on the tubes to wedge the block unit by cam action of the eccentric contacting surfaces. 60
- 65 7. The combination with spaced parallel cylindrical tubes, of a block unit mounted thereon and therebetween comprising two block members, said members having curved tube recesses, curved contacting surfaces opposite said recesses and eccentric with respect thereto and said members having abutments, a rigid member spanning the space between and contacting said tubes, and adjustable stress means acting between the abutments on the block members and the rigid member and operative to swing the block members on the tubes to wedge the block unit by cam action 70 of the eccentric contacting surfaces. 75
8. The combination with spaced parallel cylindrical tubes, of a block unit mounted thereon and therebetween comprising two block members, said members having curved tube recesses, curved contacting surfaces opposite said recesses and eccentric with respect thereto and said members having abutments, a rigid member spanning the space between and contacting said tubes, and stress means comprising a T-shaped bolt and a nut threaded thereon acting between the abutments on the block members and the rigid member and operative to swing the block members on the tubes to wedge the block unit by cam action of the eccentric contacting surfaces. 10
9. The combination with spaced parallel cylindrical tubes, of a block unit mounted thereon and therebetween comprising two block members, said members having curved tube recesses, curved contacting surfaces opposite said recesses and eccentric with respect thereto and said members having abutments, a rigid member spanning the space between and contacting said tubes, and stress means comprising a pintle, eye-bolt and nut acting between the abutments on the block members and the rigid member and operative to 15 swing the block members on the tubes to wedge the block unit by cam action of the eccentric contacting surfaces. 20
10. The combination with spaced tubes of a wall adapted to be exposed to heat, of a block unit mounted forwardly thereon and therebetween comprising two block members, said block members having tube recesses and curved contacting surfaces opposite said recesses and eccentric with respect thereto and oppositely disposed recessed surfaces providing rearwardly converging surface portions between the tubes, a rearwardly disposed rigid member spanning the space between and contacting said tubes, and stress means acting against said rigid member and against the converging surface portions on both block members to stress the block members and the rigid member against the tubes. 30
- 35 11. The combination with spaced tubes of a wall adapted to be exposed to heat, of a block unit mounted forwardly thereon and therebetween comprising two block members, said block members having tube recesses and curved contacting surfaces opposite said recesses and eccentric with respect thereto and oppositely disposed recessed surfaces providing rearwardly converging surface portions between the tubes, a rearwardly disposed rigid member spanning the space between and contacting said tubes, and stress means acting against said rigid member and against the converging surface portions on both block members to stress the block members and the rigid member against the tubes, said stress means comprising a threaded member passing through said rigid member and a nut threaded thereon. 45
- 50 12. The combination with spaced tubes of a wall adapted to be exposed to heat, of a block unit mounted forwardly thereon and therebetween comprising two block members, said block members having tube recesses and curved contacting surfaces opposite said recesses and eccentric with respect thereto and oppositely disposed recessed surfaces providing rearwardly converging surface portions between the tubes, a rigid member spanning the space between and contacting said tubes, and stress means comprising co-acting adjustable threaded parts acting in tension between said rigid member on the one hand and the converging surface portions on both block members on the other hand to stress the block 55 members. 65
- 70 75

members and the rigid member against the tubes.

13. The combination with spaced parallel tubes, of a block unit mounted thereon and therebetween comprising two block members, said block members having tube recesses and curved contacting surfaces opposite said recesses and eccentric with respect thereto and oppositely disposed surfaces between said tubes, said surfaces comprising portions angularly disposed with respect to the plane of the tubes, a rigid member spanning the space between and contacting said tubes, and stress means acting against said angularly disposed portions of said surfaces and against said rigid member to stress the block members and the rigid member against the tubes.

14. The combination with spaced parallel tubes, of a block unit mounted thereon and therebetween comprising two block members, said block members having tube recesses and curved contacting surfaces opposite said recesses and eccentric with respect thereto and oppositely disposed surfaces between said tubes, said surfaces comprising portions angularly disposed with respect to the plane of the tubes, a rigid member spanning the space between and contacting said tubes, and stress means acting against said angularly disposed portions of said surfaces and against said rigid member to stress the block members and the rigid member against the tubes, said stress means comprising a threaded member passing through said rigid member and a nut threaded thereon.

15. A structure of the character set forth comprising a two-part block unit, each part having a lateral tube engaging surface, a curved contacting surface and an opposite surface, the opposite surfaces of the parts being angularly disposed in operative position, and means for mounting the block unit comprising a rigid member and stress means comprising cooperating adjustable threaded members operative to produce pressure between the angularly disposed surfaces.

16. The combination with parallel spaced tubes, of a two-part block unit mounted thereon and therebetween comprising two block members, said block members having curved tube recesses and curved contacting surfaces opposite said recesses and eccentric with respect thereto and opposite surfaces non-concentric with respect to the tube recesses and angularly disposed with respect to each other and with respect to the plane of the tubes, and means for mounting the block unit on the tubes comprising a rigid member spanning the space between and contacting the tubes and cooperating adjustable threaded members operative to produce pressure between the angularly disposed surfaces, between the block members, between the block members and the tubes, and between the rigid member and the tubes.

17. The combination with parallel spaced tubes, of a two-part block unit mounted thereon and therebetween comprising two block members, said block members having curved tube recesses and curved contacting surfaces opposite said recesses and eccentric with respect thereto and opposite surfaces non-concentric with respect to the tube recesses and angularly disposed with respect to each other and with respect to the plane of the tubes, and means for mounting the block unit on the tubes comprising a rigid member having a portion in contact with said opposite angularly disposed surfaces and means engaging the block members and the rigid member and tending to spread apart the opposite angularly disposed surfaces to thereby produce pressure between the block members and the rigid member against the tubes.

curved contacting surfaces and wedge the block members against the tubes.

18. The combination with parallel spaced tubes, of a two-part block unit mounted thereon and therebetween comprising two block members, said block members having curved tube recesses and curved contacting surfaces opposite said recesses and eccentric with respect thereto and opposite surfaces non-concentric with respect to the tube recesses and angularly disposed with respect to each other and with respect to the plane of the tubes, and means for mounting the block unit on the tubes comprising a rigid member having a portion in contact with said opposite angularly disposed surfaces and adjustable means engaging the block members and the rigid member and tending to spread apart the opposite angularly disposed surfaces to thereby produce pressure between the curved contacting surfaces and wedge the block members against the tubes.

19. The combination with parallel spaced tubes, of a two-part block unit mounted thereon and therebetween comprising two block members, said block members having curved tube recesses and curved contacting surfaces opposite said recesses and eccentric with respect thereto and opposite surfaces non-concentric with respect to the tube recesses and angularly disposed with respect to each other and with respect to the plane of the tubes, and means for mounting the block unit on the tubes comprising a rigid member having a portion in contact with said opposite angularly disposed surfaces and threaded means engaging the block members and the rigid member and tending to spread apart the opposite angularly disposed surfaces to thereby produce pressure between the curved contacting surfaces and wedge the block members against the tubes.

20. The combination with parallel spaced tubes, of a two-part block unit mounted thereon and therebetween comprising two block members, said block members having curved tube recesses and curved contacting surfaces opposite said recesses and eccentric with respect thereto and opposite surfaces non-concentric with respect to the tube recesses and angularly disposed with respect to each other and with respect to the plane of the tubes, and means for mounting the block unit on the tubes comprising a rigid member having a portion in contact with said opposite angularly disposed surfaces and separate threaded means engaging the rigid member and each of the block members and tending to spread apart the opposite angularly disposed surfaces to thereby produce pressure between the curved contacting surfaces and wedge the block members against the tubes.

21. The combination with spaced parallel cylindrical tubes, of a block unit mounted thereon and therebetween comprising two block members, said members having curved tube recesses, curved contacting surfaces opposite said recesses and eccentric with respect thereto and said members having knuckles disposed so as to interfit and align with the knuckles on the other member, a pintle passing through said knuckles, a rigid member spanning the space between and contacting said tubes, and stress means engaging the pintle and the rigid member and operative to swing the block members on the tubes to wedge the block unit between the tubes by cam action of the eccentric contacting surfaces.

22. The combination with spaced parallel cylindrical tubes, of a block unit mounted thereon and therebetween comprising two block members,

5 said members having curved tube recesses, curved contacting surfaces opposite said recesses and eccentric with respect thereto and said members having knuckles disposed so as to interfit and align with the knuckles on the other member, a
10 pintle passing through said knuckles, a rigid member spanning the space between and contacting said tubes, and threaded means engaging the pintle and the rigid member and operative
15 to swing the block members on the tubes to wedge the block unit between the tubes by cam action of the eccentric contacting surfaces.

20 23. The combination with spaced parallel cylindrical tubes, of a block unit mounted thereon and therebetween comprising two block members, said members having curved tube recesses, curved contacting surfaces opposite said recesses and eccentric with respect thereto and said members having knuckles disposed so as to interfit and align with the knuckles on the other member, a
25 pintle passing through said knuckles, a rigid member spanning the space between and contacting said tubes, and adjustable stress means engaging the pintle and the rigid member and operative to swing the block members on the tubes to wedge the block unit between the tubes by cam action of the eccentric contacting surfaces.

24. The combination with spaced parallel cylindrical tubes, of a block unit mounted thereon and therebetween comprising two block mem-
30

bers, said members having curved tube recesses, curved contacting surfaces opposite said recesses and eccentric with respect thereto and said members having knuckles disposed so as to interfit and align with the knuckles on the other member, a
5 pintle passing through said knuckles, said pintle having a transverse cross-sectional area smaller than the transverse area of the apertures in the knuckles, a rigid member spanning the space between and contacting said tubes, and
10 stress means engaging the pintle and the rigid member and operative to swing the block members on the tubes to wedge the block unit between the tubes by cam action of the eccentric contacting surfaces.

15 25. The combination with spaced parallel cylindrical tubes, of a block unit mounted thereon and therebetween comprising two block members, said members having curved tube recesses, curved contacting surfaces opposite said recesses and eccentric with respect thereto and said members having abutments, a rigid member spanning the space between and contacting said tubes, and
20 stress means comprising a bolt and a nut threaded thereon acting between the abutments on the block members and the rigid member and operative to swing the block members on the tubes to wedge the block unit by cam action of the eccentric contacting surfaces.
